UNITED STATES PATENT OFFICE.

LOUIS EDGAR CLEMENT, OF ROCK ISLAND, QUEBEC, CANADA.

CASH-REGISTER.

1,337,441.

Specification of Letters Patent. Patented Apr. 20, 1920.

Application filed February 11, 1919. Serial No. 276,428.

To all whom it may concern:

Be it known that I, LOUIS EDGAR CLEMENT, residing at Rock Island, in the county of Stanstead, in the Province of Quebec, in the Dominion of Canada, have invented certain new and useful Improvements in Cash Registers; and I do hereby declare that the following is a full, clear, and exact description of the same.

10 The present invention relates to improvements in cash registers and it consists of an attachment preferably applied to the front of the drawer and provided with a plurality of keys which bear the different denominations of money, the arrangement being such that the cash drawer cannot be completely opened without pressing downward one of these keys.

The main object of the invention is to 20 provide a device of this character which is so constructed that a clerk receiving a bill in payment of a sale must necessarily press downward a key corresponding to the denomination of the bill before the cash 25 drawer will open. In so doing the clerk cannot forget the amount received when he gives change as the key will remain in its depressed position until it is necessary to open the drawer again. Thus errors in remitting the change will be eliminated and the clerk will be unable to claim that he had forgotten the amount given to him in payment of a sale.

A further object of the invention is to 35 provide a device that can be easily applied to a cash register without altering or changing its mechanism and which is entirely independent therefrom.

Another object of the invention is to provide a device of this character which will be 40 of simple construction and which can be readily applied, at will, to existing cash registers.

The invention will be understood with the aid of the accompanying drawings in which:

Figure 1 is a front view of a cash register with the invention applied thereto.

Fig. 2 is a side elevation of Fig. 1.

50 Fig. 3 is a side view showing the invention applied to the drawer which is shown partly opened.

Fig. 4 is an inside view showing the keys and operating mechanism, a portion being 55 broken away.

Fig. 5 is a view of the movable drawer unlocking plate.

Fig. 6 is a cross section view through the casing showing a key in its normal position.

Fig. 7 is a similar view showing the key in 60 its operative position.

Fig. 8 is a perspective view of the drawer releasing catch.

Fig. 9 is a top elevation view of the key board showing the numerals on the different 65 keys.

Like numerals of reference indicate corresponding parts in each figure.

In the drawings, 1 indicates a cash register of the usual type, for example, that 70 manufactured by National Cash Register Company, provided with a movable drawer 2 which slides in the drawer casing 3, said drawer being provided preferably on one side thereof, in the bottom with a slot 4. 5 75 is a casing preferably of the same size as the front member of the drawer and adapted to be secured to said drawer member by any suitable means. Said casing 5 is provided with a beveled surface 6 provided with a 80 plurality of holes 7 suitably distanced from one another, and 8 is an inwardly projecting flange provided with holes 9 located equidistantly from one another and in alignment with holes 7. Below said inwardly 85 projecting flange 8 are two parallel inwardly projecting flanges 10 and 11, also provided with holes 12 and 13 which align with the holes 9 and 7.

Movably secured in each set of holes 7, 9, 90 12 and 13 is a key 14 provided with the usual head 15 on which is printed or otherwise provided a numeral 16, adapted to correspond with the denomination of a bill, said key having at the lower end of its stem 95 a notch or recess 17 and below which is a tapered portion 18.

A slidable plate 19 is provided in between the flanges 10 and 11, and 20 are a plurality of holes which partially register with the 100 holes 12 and 13 in said flanges. Below said plate 19 at one side thereof is provided a downward projecting lug 21, and 22 is a tension spring secured at one end to said plate 19 and at its other end to the edge of 105 the flange 10.

It will readily be seen that on pressing down one of the keys 14, the tapered end 18 of the key will push the said plate 19 to one side, thereby moving the lug 21 and causing 11.

the lever 23 which is fulcrumed at 24 and provided with a beveled lug 25, which contacts with said lug 21 to be actuated. When the key is moved downward to such an extent that its notch 17 enters the corresponding hole 20 in the plate 19, the controlling spring 22 will snap said plate back into its former position, thereby locking the key 14 in its depressed position. Each of the keys 10 14 is provided with a spiral spring 26 around its stem whereby when another key is operated, the key which is held down, when released from the plate 19, will be brought back to its normal position simultaneously with the operation of another key.

The lever 23 is provided at one end, as has been explained above, with a beveled lug 25 and below said lug 25, is secured a spiral spring 27 which is secured in between 20 said lever and the bottom of the casing 5, so that when the said lever 23 is actuated by the lug 21 on the plate 19 it will be pushed upward into its normal position. At the other end of said lever 23 is provided 25 a catch element 28 which preferably projects outwardly at a right angle thereto, and so arranged as to normally engage the lower edge of the drawer casing 3. Naturally when the lever 23 is actuated, the catch is 30 lifted out of engagement with the drawer casing 3, and the drawer, being released, will be opened in the usual way.

To better understand the use and operation of the invention, it may be said that 35 the cash register is operated in the usual way, *i. e.*, by pressing the keys to correspond with the amount of the sale. The drawer will be opened say a few inches; that is, the length of the catch element. Immediately after operating the cash register, one 40 of the keys 14 corresponding to the denomination of the bill received in payment of the sale, is depressed thereby releasing the drawer which will be fully opened.

45 In case two bills of the same denomination are presented to the clerk for payment of successive sales, the operations concerned with the first sale are as above described, the particular unlocking or special key corresponding to the denomination of the bill being depressed to enable the drawer to move outward to fully-open position, as has been explained. This key remains depressed at the completion of the operation and, of course, cannot again be depressed when the 55 second sale takes place; but any one of the other special unlocking keys may, however, be depressed to release the drawer and the key already depressed, the latter serving in such instance as a check upon the clerk to impress upon him the denominational identity of the two bills.

What I claim as my invention is:

60 1. A device of the character described, in combination with the drawer of a cash reg-

ister, comprising a casing secured to said drawer, a plurality of denominational keys mounted in said casing, a locking element suitably mounted in said casing adapted to engage one of the sides of the drawer casing and means to operate said locking element whereby the drawer may be opened substantially as described. 70

2. A device of the character described, in combination with the drawer of a cash register, comprising a casing secured to said drawer, a plurality of denominational keys movably mounted in said casing, a locking element adapted to engage one of the sides of the drawer casing, a plate slidably and horizontally mounted in said casing, and means, whereby, by pressing on one of said keys the said plate and said locking element will be actuated to release the drawer substantially as described. 75 80

3. A device of the character described in combination with the drawer of a cash register, comprising a casing secured to said drawer, a plurality of movable denominational keys mounted in said casing, a locking element adapted to engage one of the sides of the drawer casing, a plate horizontally movably secured in said casing and having a plurality of holes, and means whereby one of said keys when pressed will 95 actuate said plate and locking element to release the drawer and means to lock said key in said plate, and whereby, said key will be released on pressing another key substantially as described. 100

4. A device of the character described, in combination with the drawer of a cash register, comprising a casing secured to said drawer, a plurality of spring held denominational keys movably mounted in said casing, each of said keys having a dent or slot intermediate of the length of its stem and a beveled lower end, a spring held plate movably secured in said casing, below the stems of said keys and provided with a plurality of holes adapted to correspond in number to the number of keys, a lever fulcrumed below said plate having at one end a catch adapted to engage the edge of the drawer casing, means whereby when one of said keys is pressed, said plate will be caused to move to and fro and engage said dent or slot on said key, means on said plate to engage said lever whereby said lever will be actuated simultaneously with said plate to unlock the 110 drawer substantially as described. 115 120

5. In a cash register, the combination of a drawer adapted to open automatically when a sales key is depressed; means for automatically stopping the drawer in partially-open position; a set of special denominational keys; and means under the control of all of the special keys for throwing out the stopping means when any special key is operated, to permit the drawer to open fully. 125 130

6. In a cash register, the combination of a drawer adapted to open automatically when a sales key is depressed; retaining means carried by the drawer to engage the drawer 5 casing of the register when the drawer has moved into partially-open position; a set of special denominational keys; and means under the control of all of the special keys for releasing the retaining means when any special 10 key is operated, to permit the drawer to open fully.

7. In a cash register, the combination of a drawer adapted to open automatically when a sales key is depressed; a catch engageable 15 with the drawer casing of the register when the drawer has moved into partially-open position to stop the drawer in that position; a set of special keys; and means under the control of all of the special keys for disengaging the catch when any special denominational 20 key is operated, to permit the drawer to open fully.

8. In a cash register, the combination of a drawer adapted to open automatically when 25 a sales key is depressed; means for automatically stopping the drawer in partially-open position; a set of special denominational keys carried by the drawer to move therewith; and means under the control of 30 all of the special keys for throwing out the stopping means when any special key is operated, to permit the drawer to open fully.

9. In a cash register, the combination of a drawer adapted to open automatically when 35 a sales key is depressed; retaining means carried by the drawer to engage the drawer casing of the register when the drawer has moved into partially-open position to stop the drawer in that position; a set of denominational special keys mounted on the drawer to move therewith; and means under the control of all of the special keys for releasing the retaining means when any special 40 key is operated, to permit the drawer to open fully.

10. In a cash register, the combination of a drawer; means for automatically locking the drawer in partially-open position; a set of denominational keys; and a single movable member under the control of all of said 50 keys operable automatically upon the depression of any one of said keys to lock that key in depressed position and simultaneously unlock the drawer to permit it to open fully.

11. In a cash register, the combination of a drawer; means automatically locking the 55

drawer in partially-open position; a set of denominational keys; and means under the control of all of said keys operable automatically upon the depression of any one of said keys to lock that key in depressed position and simultaneously unlock the drawer to permit it to open fully. 60

12. In a cash register, the combination of a drawer; a catch for locking the drawer in partially-open position; a set of denominational keys; and a member under the control of all of said keys for releasing the catch when any one of said keys is actuated, 70 to permit the drawer to open fully.

13. In a cash register, the combination of a drawer; a lock for holding it against movement; a set of denominational keys; and a slide operable upon the actuation of 75 any one of said keys for releasing said lock to permit movement of the drawer.

14. In a cash register, the combination of a drawer; a lock for holding it against movement; a set of denominational keys and 80 a slide operable upon the actuation of any one of said keys for releasing said lock to permit movement of the drawer, said slide and keys having coöperating means for preventing return movement of the key actuated. 85

15. In a cash register, the combination of a drawer; a lock for holding it against movement; a set of denominational keys; and a slide operable upon the actuation of 90 any one of said keys for releasing said lock to permit movement of the drawer, said slide and keys having coöperating means acting to prevent return movement of the key actuated and to release that key upon 95 the actuation of a second key.

16. In a cash register, the combination of a drawer; a catch for holding it against movement; a movable plate adapted to engage and release the catch; and a set of denominational keys each having a cam to operatively engage said plate. 100

17. In a cash register, the combination of a drawer; a catch for holding it against movement; a movable plate having a cam 105 to engage and release the catch; and a set of denominational keys each having a cam to operatively engage the cam on said plate.

Signed at Montreal, Quebec, Canada, this 18th day of November 1918.

LOUIS EDGAR CLEMENT.
